United States Patent Office

Des. 197,520
Patented Feb. 18, 1964

197,520

OUTDOOR RECEPTACLE COVER

Frank G. Bellek, Chicago, Ill., assignor to Bell Electric Company, Chicago, Ill., a corporation of Illinois

Filed July 11, 1961, Ser. No. 65,880

Term of patent 14 years

(Cl. D26—13)

FIG. 1

FIG. 2

FIG. 3

FIG. 4

FIG. 5

FIG. 1 is a face plan view of an outdoor receptacle cover showing my new design;

FIG. 2 is a side elevational view, the opposite side being substantially a mirror image thereof;

FIG. 3 is a face plan view thereof with a portion moved to an alternate position;

FIG. 4 is a top edge view thereof; and

FIG. 5 is a bottom edge view thereof.

I claim:

The ornamental design for an outdoor receptacle cover, as shown and described.
